UNITED STATES PATENT OFFICE.

MORITZ MENKUS, OF SAN FRANCISCO, CALIFORNIA.

DESIGN FOR A COMBINED ASH TRAY AND HUMIDOR.

Application filed May 17, 1923. Serial No. 6,173. Term of patent 3½ years.

To all whom it may concern:

Be it known that I, MORITZ MENKUS, a citizen of the United States, residing at the city and county of San Francisco and State of California, have invented a new, original, and ornamental Design for Combined Ash Tray and Humidor, of which the following is a specification, reference being had to the accompanying drawings, forming part thereof.

Fig. 1 is a side elevation of the combined ash tray and humidor, showing my new design.

Fig. 2 is a plan view of the same.

I claim:

The ornamental design for a combined ash tray and humidor, as shown.

MORITZ MENKUS.
